UNITED STATES PATENT OFFICE

166,958

CIGARETTE HOLDER

Irving Florman, New York, N. Y.

Application February 6, 1952, Serial No. 18,418

Term of patent 14 years

(Cl. D85—8)

To all whom it may concern:

Be it known that I, Irving Florman, a citizen of the United States of America, and residing at 2 West 46 Street, city of New York, county of New York, State of New York, have invented a new, original, and ornamental Design for a Cigarette Holder, of which the following is a specification, reference being made to the accompanying drawing, forming part thereof.

Fig. 1 is a side view of a cigarette holder, showing my new design;

Fig. 2 is an end view thereof, looking at the left end in Fig. 1; and

Fig. 3 is an end view thereof, looking at the right end in Fig. 1.

In the drawing a portion of Fig. 1 is shaded to indicate transparency.

I claim:

The ornamental design for a cigarette holder, substantially as shown and described.

IRVING FLORMAN.
